DIAPHRAGM COVER FOR LIQUID STORAGE TANKS

Fred L. Plummer, Warren, Pa., assignor to Hammond Iron Works, Warren, Pa., a corporation of Pennsylvania

Application April 17, 1948, Serial No. 21,603

1 Claim. (Cl. 220—85)

1

This invention relates to closed liquid-storage metallic tanks more particularly of the type that is adapted to hold volatile liquids such as are derived from petroleum, of the type of high octane gasoline, and in which tank the amount of the liquid stored therein fluctuates so that the liquid-level in the tank varies. It is an object of this invention to eliminate from such tanks all major vapor-receiving or accumulating air spaces for thereby preventing the formation of an air-vapor mixture of all liquids having a vapor-pressure less than atmospheric pressure so no gases are formed which can escape. It is a further object of this invention to devise an impervious flexible diaphragm that is at all times in contact with the liquid-level of a liquid stored in the tank, whose purpose is to prevent the escape of gas that may have become volatilized from the liquid and also to prevent contaminants from getting into the liquid. To that end, it is proposed to support a generally bucket-shaped diaphragm from the inner wall of the tank at an elevation intermediate the height of the tank wall, but to so support the diaphragm that its bottom closure section rises and falls with the rise and fall of the liquid-level in the tank yet without causing disruptive friction between the cylindrical or tubular side-wall section of the diaphragm and the metallic tank wall.

When the tank is substantially empty of liquid, the bucket-shaped diaphragm hangs or depends from its wall support, and it takes its normal bucket-shaped form or contour. But as the liquid-level rises in the tank and the bottom section of the diaphragm rises therewith, provision must be made for taking up or allowing for the folding of the excess material of the diaphragm, so it is another object of this invention so to arrange and design the diaphragm that this excess material will be taken up or form a depending main deformation fold and the folding thereof is to be controlled so that it is of generally substantially continuous annular extent or pattern while being so disposed that it is always located at a distance from the tank wall, in other words, that the deformation pattern or patterns are always in the bottom section of the diaphragm. Another object is to prevent as far as possible the sides of the diaphragm from coming into contact with the tank wall while the bottom section of the diaphragm is below the circumferential line of support of the diaphragm wall. A still further object is to design such a diaphragm that as its bottom section rises above the line of support of the diaphragm walls, that part of the

2

diaphragm walls which comes into contact with the tank wall will contact the tank wall in a rolling-on fashion, and when leaving the tank wall will leave it in a peeling-off fashion. This action will assure minimizing harmful friction between the diaphragm and the tank wall, as well as assuring a smooth contact between the two at all times and the avoidance of wrinkles that may break through or cause cracks in the diaphragm.

10 Such a diaphragm can be used to equip existing metal tanks not now suitable for storing highly volatile liquids, instead of building new specially designed tanks as is now necessary. In other words, this type of diaphragm offers a cheap and effective way of converting present non-appropriate tanks into tanks that are highly appropriate to store valuable volatile liquids.

The best embodiment of the invention now known to me has been chosen for illustrative purposes, but this embodiment should be viewed as being illustrative only and not as limiting because obviously the invention is capable of other embodiments having revised details and construction, so long as they fall within the ambit 20 of the appended claim.

The invention is illustrated in the accompanying drawings in which Fig. 1 shows a vertical sectional view through a tank equipped with the diaphragm of this invention. Variant positions 30 taken by the diaphragm are shown in broken lines. Fig. 2 is a partial isometric view of the diaphragm with parts thereof broken away so that its interior construction may be seen. Fig. 3 is another partial sectional isometric view of 35 the diaphragm with parts broken away to show the cover-strip arrangement for securing together abutting edges of the flexible material of the bottom sections. Fig. 4 is a partial vertical sectional view showing the construction of the 40 diaphragm-supporting rim on the interior of the tank with the means for fastening the free or upper edge of the diaphragm thereto. Fig. 5 is a partial sectional and isometric view through a section of the annular fold that develops in the 45 bottom of the diaphragm during its rise and fall. Fig. 6 is a plan view of the diaphragm in a position when its bottom exhibits the fold—this view showing substantially annular form or pattern taken by the fold. Fig. 7 is a view looking upwardly at the diaphragm from the bottom while it is in the same position as in Fig. 6. Figs. 8, 9 and 10 are similar sectional isometric views showing the diaphragm in three different positions below the diaphragm-supporting rim, while 50 Figs. 11, 12 and 13 are somewhat similar views

showing three different positions of the diaphragm above the diaphragm-supporting rim. Fig. 14 is a partial sectional view showing how the wall-section of the diaphragm rolls on or against the tank wall when it is above that diaphragm-supporting rim, while Fig. 15 is a similar view but showing the peeling-off action that takes place when the diaphragm wall leaves the wall of the tank. Fig. 16 is a vertical sectional view through the tank showing one lower variant position of the diaphragm when weighting water or other liquid is supplied and carried by the upper surface of the diaphragm, while Fig. 17 is a similar view but with the diaphragm in an upper variant position and shows the water-film that forms between the wall of the diaphragm and the wall of the tank.

In the drawings, and particularly Fig. 1 thereof, 11 indicates a liquid-holding metallic tank having a bottom 12, side wall 13, and top 14, which when of larger diameters such as more than 50 feet may be trussed as at 15 should the size of the tank warrant it. Such tanks are usually vented as for instance at 16 or some equivalent thereof. The tank can be filled with liquid, or liquid withdrawn therefrom by some suitable pipe or conduit 17. Just above the horizontal center or median of the tank there is provided a substantially annular support or rim 18 from which is hung a bag-like or bucket-shaped diaphragm indicated generally by the numeral 20 having side walls or a tubular side wall section 21 and a bottom or bottom-closure section 22. The diaphragm is made of flexible gas- and liquid-impermeable material such as liquid- and gas-proofed fabric but preferably nylon cloth coated on both sides with a synthetic rubber material such as neoprene or Buna-N-type. The walls can be made of vertically extending strips 19 secured together (Fig. 2). The bottom 22 comprises a disc-like piece of such flexible material formed of strips 23 of such material suitably secured together to form the bottom, with the abutting edges of such strips cemented together and preferably with cover-strips 24. The periphery or peripheral edge 25 of the bottom 22 is secured or cemented to the lower edge 26 of the side walls 21 of the diaphragm 20 by weighting means comprising joint-covering devices such as annular upper cover-strips 27 and an annular lower cover-strip 28, both covering and protecting the juncture of the abutting edges 25 and 26. The diaphragm-support numbered generally as 18 is shown in detail in Fig. 4 wherein it can be seen that this assembly comprises a substantially annularly extending angle iron 30 having a horizontal portion 31 and a vertical flange or rim portion 32. The horizontal portion 31 is secured to the inside of the tank wall 13 by means of an upper weld 33 and a lower weld 34. A further weld 35 is provided against which bears or is jammed a lead or other deformable strip 36 for frictionally securing in place in supporting position the upper or free end of the walls 21 of the diaphragm 20.

Fig. 1 shows the parts with little or no liquid in the tank 11 so that the diaphragm hangs from its support 18 in a true bucket-like shape or formation and in position A'. Suppose now that enough liquid is pumped into the tank beneath the bottom 22 of the diaphragm to provide enough liquid-pressure exerted on the diaphragm bottom from below to cause that bottom to be raised by its floating contact with the liquid-level of the liquid so that the diaphragm will then as-

sume the dotted line position A'' indicated on Fig. 1. In so rising with the liquid-level a substantially annular main depending fold 40 will develop which is shown in more detail in Figs. 5, 6 and 7. This generally annular fold seems to develop in substantially the same place, for reasons now thought to be due to the weighting effect of the double or dual cover-strips 27 and 28 respectively above and below the diaphragm bottom 22. As the liquid-level in the tank rises, the diaphragm will then take a position and form indicated in Fig. 1 as at A'''. Position A' is shown in greater detail in Fig. 8, position A'' in Fig. 9 and position A''' in Fig. 10—all being at or below the elevation of the diaphragm-supporting rim or flange 18. It will be noted that the annularly extending fold 40 progressively elongates downwardly as these rising positions are taken; that the dual cover-strips 27 and 28 always seem to be at the bottom of the fold, and that in these variant positions the wall section 21 of the diaphragm 20 is drawn away or spaced from the side wall 13 of the tank 11. As the diaphragm passes from position A' to A'', and from A'' to A''', for instance, the diameter of the annular fold, or more particularly the annular cover-strips 27 and 28, must diminish. This lessened diameter is accomplished by increased irregularity or by folding or undulating both vertically and circumferentially of the fold 40, as is attempted to be illustrated in Figs. 5 and 6, but especially in Fig. 7 which is a view looking up at the fold from beneath the diaphragm. Indeed, smaller or minor folds are superposed on the larger or main annular fold 40 so that the latter becomes what may be termed a composite fold.

However, as the liquid-level rises further and lifts the bottom 22 of the diaphragm to an elevation above that of the flange 18, a slightly different condition exists. Dotted line position B' in Fig. 1 shows the new condition, namely that the upwardly extending portion of a section of the diaphragm walls 21 is in actual contact with tank wall 13. This condition continues as the next higher position B'' is assumed, and in its highest position B''''. Position B' is shown in enlarged detail in Fig. 11, B'' in Fig. 12 and B''' in Fig. 13. In other words, the diameter of the upwardly extending section of the diaphragm walls 21 is greater than the diameter of the corresponding section of the same walls when they are in depending position instead of upwardly extending, that is when they are below the diaphragm-support 18. However, even in the upper positions B' and B'' the same annular folding 40 takes place. When the diaphragm is raised or lifted by liquid therebeneath to an elevation above the support 18, that section of the diaphragm walls 21 that comes into contact with the tank wall 13 does so in a rolling-on fashion as shown in Fig. 14 (indicated by arrows) so there is a minimum of rubbing friction between the two. On the other hand, when the liquid-level begins to fall and the diaphragm bottom goes from position B''' to position B'', or from B'' to B', that part of the diaphragm wall that is in contact with the tank wall leaves the latter in a peeling-off fashion, as shown in Fig. 15 (indicated by arrows), for similarly minimizing friction or rubbing. In smaller diameter tanks using a self-supporting dome roof without truss supports the full capacity of the tank can be used by having the diaphragm, when in position B''', bear against the dome roof.

The path taken by the substantially annular

fold 40, whose general annularity of pattern in plan view is shown in Fig. 6, however irregular it may be in practice, is a curved line, shown by the dot-and-dash line C in Fig. 1 and probably generally parabolic. This is because the diaphragm must telescope in its diameter as it assumes positions anywhere between its extreme upper and lower positions. The path above the diaphragm-supporting rim has a different curvature from that part of the path therebelow. The reason is because the diameter assumed by the diaphragm when above the supporting rim is greater than when the diaphragm is therebelow.

It will be seen from Figs. 1, 5 to 7, and 9 to 12, that the wall section 21 of the diaphragm assumes an angular formation in all but its extreme upper and lower positions. That is, the wall section has a vertical section adjacent the support devices that then merges into, or has derived therefrom, a generally horizontal annular spacing section lying between the fold and the vertical section.

Since an important feature of this invention is the control of the folding of the diaphragm so that it assumes localized substantial annularity, which control is exercised by particularized weighting, other weighting means obviously can be used or substituted for the cover-strip arrangement 27 and 28 so long as they produce the substantially annular folding or deformation pattern in the bottom of the diaphragm. For instance, it is possible to use a single cover-strip instead of two superposed strips such as 27 and 28, and sometimes it may be desirable merely to lap adjacent edges of pieces or strips of the fabric of the bottom. Also this centralizing of the folding can be emphasized by the use of a quantity of weighting liquid on top of the diaphragm bottom 22. Fig. 16 shows how such liquid 41 acts when the diaphragm assumes a position such as position A'', while Fig. 17 shows how such liquid 41 acts when the diaphragm assumes such a position as B''. The liquid may be water, or a salt solution, or indeed any liquid that tends to emphasize the fold 40. A sufficient quantity of such weighting liquid 41 can be used so that when the diaphragm assumes an upper position, such as B'', some of the liquid will run over and down the side walls 21 of the diaphragm to reside between those walls and the walls of the tank, as shown in Fig. 17, where it serves as a friction-preventing film or layer 42.

It is sometimes desirable to supply a valve controlled pipe 44 in the side wall 13 of the tank and just below the diaphragm-support 18 provided so that before liquid is pumped into the tank most of the air below the diaphragm can be evacuated pulling the diaphragm close to the bottom and shell of the tank and eliminating excess air spaces. The valve could also be used to evacuate an excess volume of air and vapor if air should be introduced by pumping through the inlet to the tank. It would not generally be used because of volatilization of the liquid stored in the tank.

Thus the invention can be practiced by providing a support for the free edge or open end of the bucket-shaped diaphragm so that the diaphragm hangs or depends from that support in a position that when the tank is empty the bottom closure or end of the diaphragm approximates but does not actually touch the bottom of the tank.

Fold-inducing means are provided to operate when the bottom of the diaphragm rises due to rise of the liquid-level in the tank. That is the necessary folding of the bottom to accomplish

the necessary shortening thereof is centralized or localized by the weighting cover-strips. The folds must take place somewhere so they seem to be induced or controlled to take place in more or less general alignment with these strips and as an increasing amount of excess material has to be taken up the general fold 40 becomes a composite one with smaller folds superposed on the larger one. Further, the general fold is thus caused always to depend from the diaphragm bottom in a more or less annular pattern downwardly into the liquid in the tank, and this seems to pull the wall of the diaphragm away from the tank wall, at least until the diaphragm bottom reaches an elevation equal to the diaphragm support on the tank.

But when the bottom of the diaphragm rises to an elevation above that support, the reverse seems to happen, namely, the walls of the diaphragm are allowed to be pressed against the wall of the tank in a gentle progressive manner that can best be described by saying that it takes place in a rolling-on manner that is substantially frictionless. This rolling-on is found to be substantially nonwrinkle-forming as the wall of the diaphragm fits the tank wall snugly and very smoothly.

When the liquid-level in the tank falls, the diaphragm walls leave the tank wall in a curving or peeling-off manner as the dependent folds increase in depth, and when the diaphragm bottom gets below the level of the supporting rim, the diaphragm walls are again maintained out of contact with the tank wall.

This functioning is satisfactory but under certain circumstances it may be desirable to supply and maintain a liquid on top of the diaphragm bottom. This liquid seems to equalize to some extent the hydraulic pressure on both sides of the diaphragm bottom in that the stored liquid pressing upwardly from beneath and the liquid on top pressing downwardly results in a pattern taken by the folds which is much more regular and more accurately localized or centralized about the cover-strips at the juncture of the diaphragm bottom and walls. Another advantage of the use of such liquid is that when the diaphragm rises above the supporting rim and its walls tend to be pressed against the tank wall, there is a film of this liquid therebetween which tends to lubricate the contacting parts to be quite frictionless.

What I claim is:

In combination with a liquid storage tank 55 adapted to have the liquid level therein vary, a diaphragm construction comprising impervious flexible material adapted to have contact with the liquid and to adapt itself to variations of the liquid level, and fastening means extending internally along the periphery of the vertical tank wall at an intermediate elevation thereof for fastening the peripheral edge portion of the diaphragm to the tank; characterized by the fact that the diaphragm comprises a vertical cylindrical portion extending from said fastening means along the vertical tank wall, an annular portion extending in a horizontal plane inwardly from said cylindrical portion and in the plane of the liquid level, a central circular portion surrounded by and co-planar with said annular portion, and a depending annular fold connecting said annular portion with said central portion, said annular fold being adapted to assume a smallest diameter, a greatest depth, and a greatest distance from the tank wall when the

liquid level substantially coincides with the elevation of the fastening means while the height of the cylindrical portion becomes a minimum, said diameter being adapted to increase as the liquid level rises or falls with respect to said elevation with a concomitant compensatory decrease in depth of the fold, a compensatory decrease of distance between the fold and the tank wall, and a compensatory increase of height of said cylindrical portion.

FRED L. PLUMMER.
